UNITED STATES PATENT OFFICE.

HENRY J. HUGHES, OF OTTAWA, ILLINOIS.

WATER-HEATER.

1,305,110.

Specification of Letters Patent. Patented May 27, 1919.

Application filed January 19, 1917. Serial No. 143,251.

To all whom it may concern:

Be it known that I, HENRY J. HUGHES, a citizen of the United States, and a resident of Ottawa, in the county of La Salle and 5 State of Illinois, have invented certain new and useful Improvements in Water-Heaters, of which the following is a specification.

My invention is an improvement in water heaters, and has for its object to provide 10 means for use in connection with the usual house boiler for heating the water within the same by conduction instead of directly, to prevent the deposit of sediment in the water back or the gas heater.

15 In the drawings:

Figure 1 is a front view of a house boiler provided with the improvement;

Fig. 2 is an enlarged partial vertical section, and

20 Fig. 3 is a section on the line 3—3 of Fig. 2.

The present embodiment of the invention is shown in connection with a house boiler 1 of the usual type, having in connection therewith a gas heater 2, the said gas heater being connected to the boiler by pipes 3 and 4. The boiler is also provided with a water inlet pipe 5 and with an outlet pipe 6. The improvement comprises an auxiliary boiler 30 in the form of a casing 8, which is seated over the lower end of the boiler 1, the lower end of the said boiler 1 being within the auxiliary boiler. The auxiliary boiler is of greater diameter than the main boiler, so 35 that an annular chamber is formed between the two and the bottom 9 of the main boiler is spaced above the bottom 10 of the auxiliary boiler by means of the feet 11 shown more particularly in Fig. 2. These feet are 40 in the present instance, four in number, and are metal straps bent into loop form and having their ends clamped to the boiler by rivets 12^a, which are passed through the ends of the loop below the edge of the main 45 boiler.

The pipe 4 before mentioned, passes through a nipple 12 in the bottom of the auxiliary tank, and a packing 13 is arranged about the pipe between the end of the nipple 50 and a packing nut 14 which is threaded onto the nipple, the packing making a water tight joint at this point. At its upper end the auxiliary boiler 8 is drawn in, as indicated at 15, to a connection with a collar 16, which encircles the boiler 1, making a tight connec-

tion at this point. The drawn in portion 15 has a door opening which is normally closed by a door 17. By means of this door opening, the auxiliary tank may be filled, and the said tank is supplied with connections 18 and 19, to a water-back W in the furnace F, by means of which the water in the auxiliary tank 8 is heated.

In comparison, the temperature of the heat from the gas heater 2 is low when compared with the temperature of the furnace water-back. A fact that has developed to be a matter of common knowledge in connection with heating apparatus of this type is, that where the city water, especially if it 70 contains such substances as lime in solution, deposits out of such substances accumulate in the pipe connections when the water is subjected to extremely high temperatures as it is when it passes through a furnace water-back. Difficulty is therefore experienced with such arrangement when it is attempted to heat the water in the boiler by means of the gas heater in the summer time when the fire in the furnace is out.

80 The result is that there can be little or no circulation of water through the boiler from the gas heater, and consequently the apparatus must be taken out and the pipe connection cleaned. The present invention overcomes all present difficulties in this respect by simply separating the high temperature heat source and the low temperature heat source from direct communication with each other and with the boiler. This is done by 85 interposing the auxiliary boiler 8 with its distilled or rain water. The furnace water-back W now having no direct connection to the main boiler and furthermore serving to heat water that contains no lime, obviously 90 can no longer be the instrument by which the pipe connections are clogged, and consequently those heat sources operate to heat the water in the boiler 1 without interference 95 from the difficulty mentioned.

100 In operation, the auxiliary tank is filled with rain water or other water that is not hard, while the ordinary city water is used in the house boiler. The water from the auxiliary boiler flows through the water back where it is heated, returning to the auxiliary boiler, and in turn heating the water in the main boiler. As is known, where hard water is used in a house boiler connected with the water back or other 110

heater, the water back and connecting pipes soon become choked by the sediment deposited by the hard water. In the present arrangement the hard water does not enter the water back nor the pipes leading thereto, being heated by the water in the auxiliary boiler, which being soft water does not deposit any sediment.

I claim:

- 10 1. In combination, a main boiler holding lime-filled water, a comparatively low-temperature heat source including a gas heater in fluid connection with said boiler, the heat from said heater being insufficiently great to cause the precipitation of lime in the main boiler fluid connections, and an auxiliary boiler holding rain water, receiving the lower portion of the main boiler, having a comparatively high-temperature heat source 15 including a furnace water-back in fluid connection with said boiler, the indirect heating of the lime-filled water in the main boiler through the auxiliary boiler also avoiding

the precipitation of lime by the action of the comparatively high-temperature heat.

2. Instrumentalities in combination enabling the heating of water from either a comparatively high-temperature heat source or a low-temperature heat source, by avoiding the precipitation of sediment in the pipe 25 connections of the high-temperature heat source, comprising in combination a main boiler holding city water in fluid connection with a gas heater, and an auxiliary boiler holding filtered water, receiving the lower 30 portion of the main boiler and in fluid connection with a furnace water-back, the comparatively high-temperature heat source of the water-back being out of communication with the main boiler, thus avoiding the clogging 35 of the gas heater pipe connections.

HENRY J. HUGHES.
